URINE SPECIMEN KIT

David L. Brodsky, Providence, R.I., assignor to Superior Plastic Products Co., Providence, R.I.

Filed June 21, 1971, Ser. No. 155,401

Term of patent 14 years

Int. Cl. D24—02
U.S. Cl. D83—1 U

FIG. 1

FIG. 2

FIG. 3

FIG. 4

FIG. 5

FIG. 6

FIG. 1 is an enlarged perspective view of a urine specimen kit with portions fragmentarily shown in cross-section for clarity of illustration;

FIG. 2 is a rear elevational view thereof;

FIG. 3 is an end elevational view, looking from the right with respect to FIG. 1;

FIG. 4 is an end elevational view, looking from the left with respect to FIG. 1;

FIG. 5 is a top plan view thereof; and

FIG. 6 is a bottom plan view thereof.

I claim:

The ornamental design for a urine specimen kit, substantially as shown and described.
